UNITED STATES PATENT OFFICE.

CHARLES H. SMITH, OF WOONSOCKET, RHODE ISLAND.

GRADUATE.

SPECIFICATION forming part of Letters Patent No. 747,249, dated December 15, 1903.

Application filed July 27, 1903. Serial No. 167,196. (No model.)

To all whom it may concern:

Be it known that I, CHARLES H. SMITH, a citizen of the United States, residing at Woonsocket, in the county of Providence and State 5 of Rhode Island, have invented new and useful Improvements in Graduates, of which the following is a specification.

My invention pertains to vessels, more particularly measuring vessels, such as apothecaries' graduates; and it has for its object to provide a vessel having a plurality of pouring-lips of different sizes.

With the foregoing in mind the invention will be fully understood from the following 15 description and claim when taken in connection with the accompanying drawings, in which—

Figure 1 is an elevation of a graduate constituting one embodiment of my invention, 20 and Fig. 2 a top plan view of the same.

Similar letters designate corresponding parts in both views of the drawings, referring to which—

A is a graduate, of glass or other suitable 25 material, provided with the ordinary or any other suitable graduated scale *a*. The said graduate is peculiar in that it embodies three pouring-lips *b c d*. These lips are of different sizes, as illustrated, and are arranged equidistant. In virtue of the graduate embodying 30 three pouring-lips it will be observed that liquid may be poured from the graduate into a bottle or other receptacle through the lip adjacent to said bottle or receptacle, and thus the necessity of turning the graduate precedent 35 to pouring liquid therefrom is obviated, which is an important advantage. Again, it will be observed that in the event of one lip being broken the graduate is not rendered useless, since liquid may be poured therefrom 40 through the remaining lips.

The provision of lips of different sizes is materially advantageous, because the large lip may be used when it is desired to quickly pour liquid into a bottle having a large mouth, 45 while the smaller lips may be used when liquid is to be poured into bottles having smaller mouths.

The three pouring-lips arranged equidistant are materially advantageous, since when the graduate is grasped to pour liquid from one lip the other lips rest above the thumb and forefinger, respectively, of the user's hand and preclude the graduate slipping through the hand. 50

It will be appreciated from the foregoing that notwithstanding the advantages which follow from the provision of the three pouring-lips my novel graduate may be produced almost, if not quite, as cheaply as the ordinary graduate; also, that the three equidistant pouring-lips add to rather than detract from the appearance of the graduate and render the same very convenient to handle. 60

Having described my invention, what I 65 claim, and desire to secure by Letters Patent, is—

As an improved article of manufacture, a graduate having three pouring-lips at its upper end; the said lips being of different sizes 70 to fit different bottles, and being arranged equidistant whereby two of the lips will necessarily rest above the thumb and forefinger of the hand when the graduate is grasped to pour liquid from the remaining lip. 75

In testimony whereof I have hereunto set my hand in presence of two subscribing witnesses.

CHARLES H. SMITH.
